HAROLD L. SAWYER, OF LYNN, AND JOHN W. COSGROVE, OF MEDFORD, MASSACHUSETTS, ASSIGNORS TO UNITED SHOE MACHINERY CORPORATION, OF PATERSON, NEW JERSEY, A CORPORATION OF NEW JERSEY.

APPARATUS FOR SOFTENING SHOE STIFFENERS

Application filed November 14, 1927. Serial No. 233,144.

This invention relates to an apparatus for softening shoe stiffeners and is herein disclosed as embodied in an apparatus for applying a solvent liquid to portions of stiffening members used in the toe portions of boots and shoes.

In the manufacture of boots and shoes it is customary to incorporate stiffeners in the uppers thereof. In order to promote brevity the invention will be described in its application to a certain type of stiffener which is adapted to be incorporated in the toe portion of the upper of a shoe. A stiffener of this type comprises a suitably shaped piece of fabric impregnated with celluloid or some hard and resilient substance which is soluble in a volatile solvent such for example as a mixture of alcohol and acetone. In the manufacture of a shoe such a stiffener is first dipped in the solvent to render it limp—and usually also sticky—and is then placed in the toe portion of the upper of the shoe. The upper, with the stiffener, is first subjected to the pulling-over operation and then to the lasting operation at the completion of which the stiffener has been conformed to the toe portion of the last. The lasted shoe is then put through the various operations which complete it, and the last is kept in the shoe until the volatile solvent has evaporated so that in the finished shoe the molded stiffener has become hard and resilient. When only a short period of time—for example three or four hours—elapses between the pulling-over and the lasting operations, no difficulty is encountered; but when—as is the case in some factories—twenty-four hours or more elapse between the two operations, the stiffeners frequently become hard, and their margins must be again treated with solvent liquid so as to resoften them prior to the lasting operation.

According to one feature of the invention there is provided an apparatus for performing the above referred to and similar softening operations comprising operator-controlled means for delivering a solvent liquid intermittently in measured quantities to a nozzle which is constructed and arranged to apply the solvent liquid continuously to the

margin of the stiffener. In the illustrated apparatus the nozzle has a constricted passage opening into a groove which serves to retain more or less of the liquid, the groove being formed in an end of the nozzle. This grooved end is thin and fan-shaped, being formed to accommodate the general curvature of the stiffener and to distribute the solvent liquid along the line to be treated. As illustrated, the constricted passage leading to the groove is of such small bore as substantially to prevent the flow of the liquid under the normal head at which the liquid is supplied, thereby ensuring that the liquid shall be delivered as desired and in relatively small amounts to avoid any danger of the liquid working through the leather and impairing the appearance of the outside of the shoe. Means are preferably provided for momentarily augmenting the normal head of the liquid to force the liquid through the constricted passage and thereby to expel a portion of the liquid into the groove. The means whereby this is accomplished may, as in the illustrated apparatus, take the form of a valve which also functions as a plunger, and which in its operative movement displaces some of the liquid and thereby temporarily augments the head of the liquid. In the illustrated construction the liquid is supplied to the valve through a flexible tube leading to the valve and nozzle, the valve being disposed within a hollow handle, and the nozzle being offset from the handle to permit access of the nozzle to the margin of the stiffener when the upper has been drawn over a last. The solvent liquid is supplied to the tube from a reservoir which, in the illustrated construction, is heightwise adjustable relatively to the normal working level of the nozzle to vary the amount of liquid allowed to pass by the constriction.

These and other features of the invention, including certain details of construction and combinations of parts, are to be explained in the following description and pointed out in the claims.

In the accompanying drawings, showing an embodiment of the invention:

Fig. 1 is a general view of the apparatus in position for use upon a shoe;

Fig. 2 is a sectional elevation through the nozzle and valve; and

Fig. 3 is a sectional plan view, showing the internal structure of the nozzle.

A reservoir 1, which may assume the form of any suitable container, is clamped upon a standard 3 by means of a clamp 5 and set screw 7, so as to permit the reservoir to be vertically adjusted upon standard 3. The lower portion of the reservoir 1 communicates with a flexible tube 9, preferably of rubber, which is secured at its further end to a metal tube 11 which leads to a valve chamber 13. Surrounding the tube 11 is a wooden handle 15 to enable the operator to grasp the device. The handle 15 is secured upon the tube 11 by means of a washer 17 threaded upon the outer or rear end of the tube 11, and the threads whereby the washer 17 is retained afford a convenient attaching means for the end of the rubber tube 9, although any other suitable method of connection may be employed.

The valve chamber 13, which is carried upon and preferably, as illustrated, is integral with the forward end of the tube 11, has a valve seat 19 concentric with, and in effect a continuation of, the tube 11, through which valve seat liquid may pass from the tube 11 to the interior of the valve chamber 13. The forward end of the valve chamber 13 is threaded to receive a plug 21 having a bore 23 concentric with the valve seat 19, the bore 23 serving as a guide for a valve plunger 25 which is adapted to cooperate with the valve seat 19 in controlling the passage of liquid into the valve chamber 13. A valve stem 27, of smaller diameter than the valve plunger 25 and secured thereto, extends through a bore in the forward end of the plug 21. A helical spring 29 surrounding the valve stem 27 and contained within the bore 23 is compressed between the forward end 45 of the plug 21 and the valve 25 and thus urges the valve to closed position. A leather washer 31 covers the seating face of the valve plunger 25. A slot 33 is provided in the forward end of the valve stem 27 outside of the plug 21, and an arm 35 of a bell crank 37 engages the slot 33 to open the valve plunger 25 against the pressure of the spring 29. The other arm of the bell crank 37 extends rearwardly and terminates in a flat thumb-piece 39 adjacent to the handle 15. The bell crank 37 is rocked about a pivot 41 mounted between a pair of ears 43 carried on a collar 45 which is secured around the forward portion of the plug 21 by means of a set screw 47. A gas- 60 ket 49 of leather or other suitable material is interposed between the collar 45 and the forward end of the valve chamber 13 to prevent leakage. The valve plunger 25 fits the bore 23 with sufficient closeness to effect a substantial seal against leakage. When re-

tracted to permit the flow of liquid through the valve seat 19, the valve plunger 25 extends partially or wholly within the bore 23. The thickness of the valve plunger 25 is such, in relation to its closing movement, that even when this member is moved under the influence of the spring 29 to fully closed position, the valve plunger 25 partially extends within the bore 23, and at all times prevents leakage through the bore. The valve stem 27 fits its bore in the end of the plug 21 loosely, to permit venting of the air or of any liquid which might be trapped within the bore 23 between the outer end of the plug 21 and the valve plunger 25.

Extending laterally from one side of the valve chamber 13 and integral therewith is a hollow cylindrical lug 51 internally threaded to receive a plug 53. The outer portion of the plug 53 is diametrically bored part way through to receive the rear end of a forwardly extending nozzle 55, which is laterally offset from the tube 11 and the valve chamber 13. The bell crank 37 is positioned on the opposite side of the valve chamber 13 from the lug 51 and the nozzle 55. The nozzle 55 is bored to form a passage 57 extending forwardly from the rear end of the nozzle; and a passage 59 in the plug 53, which extends laterally with respect to the nozzle 55, communicates at one end with the passage 57 and at the other end with an outlet opening 61 in the side wall of the valve chamber 13, thereby connecting the interior of the nozzle with the interior of the valve chamber.

The nozzle 55 is of cylindrical form except for its forward end (Fig. 3) which is gradually flattened to a relatively thin edge 63 of about one-sixteenth of an inch in thickness, the forward end of the nozzle also being gradually broadened as the edge 63 is approached. The edge 63 is rounded to a convex curve for convenience in application to the generally curved portions of work such as a shoe toe stiffener. The gradual broadening and flattening of the forward end of the nozzle 55 together with the curvature of the edge 63 give this end a fan-shaped appearance. The edge 63 is grooved, as at 65, to a width and depth of somewhat less than one-sixteenth of an inch, the groove 65 following the curvature of the edge 63. The passage 57 does not extend all the way to the forward end of the nozzle 55, but is continued by a passage 67 of reduced diameter to accommodate the flattened end of the nozzle. The passage 67 is connected to the groove 65 by a constricted passage 69. A diameter of slightly less than one thirty-second of an inch has proved satisfactory for the constricted passage 69, and it need not be over a quarter of an inch in length. While several radiating constricted passages may be provided to connect the passage 67 with the groove 65, a single constricted passage has proved satisfactory.

To use the device, the operator fills the container 1 with a mixture of alcohol and acetone, or with other solvent liquid, adjusting the container to suitable height on the stand 5 and 3 as will be hereinafter explained. Grasping the handle 15, he applies the forward edge 63 of the nozzle 55 to the portions of the fabric stiffener which he desires to soften preparatory to the securing of these 10 portions over the edge of the last. There is thus actual contact between the nozzle and the work. Fig. 1 shows the device in position for operation upon a shoe S having fabric stiffening members F, the device being 15 constructed and arranged so that, if desired, shoes carried on a rack may be treated without removing them from the rack. The groove 65, by virtue of its small width and depth, always retains more or less of the liquid, and will therefore distribute the liquid uniformly and continuously along the line to be treated, regardless of the intermittent operation of the control valve. The operator 20 controls the supply of liquid, as he desires, by manipulation of the thumb-piece 39. Upon opening the valve by the retraction of the valve plunger 25, practically no liquid will issue from the nozzle 55, because of the retarding effect of the constricted passage 69. 25 By permitting the valve to close, however, under the influence of the spring 29, the valve plunger 25 will displace a portion of the liquid within the valve chamber 13, thereby setting up a momentary pressure within the 30 valve chamber and forcing a portion of the displaced liquid through the constricted passage 69 into the groove 65. The greater portion of the liquid displaced by the valve plunger 25 will thus be expelled through the 35 nozzle 55 rather than be forced back into the tubes 11 and 9, because the inertia of the long column of liquid contained in these tubes, as well as the fluid head, will oppose the momentary pressure. The intermittent operation 40 of the thumb-piece 39 will therefore effect the delivery of the liquid as required, depending upon the frequency of manipulation by the operator. As only a very small amount of the liquid will be delivered for each release 45 of the thumb-piece, danger of injury to the leather by excessive quantities of the liquid may be avoided. By adjusting the container 1 to a greater or less height relatively to the 50 level of the point of use of the nozzle 55, a greater or less fluid head may be obtained, so that when the container 1 is adjusted to a 55 relatively high level, more of the liquid displaced by the closing movement of the plunger 25 will be expelled from the nozzle 55, and less of the displaced liquid will be allowed to 60 flow back into the tube 11; while if the container 1 is adjusted to a relatively low level, less of the displaced liquid will be expelled from the nozzle 55 and more will be allowed 65 to flow back into the tube 11. It will be

noted that for every adjustment of the height of the container 1, the amount of the liquid delivered to the groove 65 will be definite, because the displacement of the liquid in the valve chamber 13 by the valve plunger 25 70 will be definite, and each manipulation of the thumb-piece 39 will therefore effect the delivery of a measured amount of the liquid.

The above described dimensions of the passage 69 and the groove 65 have been given 75 merely as a guide, and these dimensions may be varied to suit the character of the work. In the following claims, the term "conduit" is not limited to the specific arrangement of elements (i. e., the groove 65, the passages 69, 80 67, 57 and 59, the opening 61, the valve chamber 13, and the tubes 11 and 9) above described, nor need the conduit terminate in a groove, except as set forth in the claims.

Having described our invention, what we 85 claim as new and desire to secure by Letters Patent of the United States is:

1. A device for softening the margin of a stiffener which has been incorporated in a partially lasted upper, having, in combination, a hollow handle through which liquid may pass, a valve within said handle, a flexible supply tube connected to said handle upon the inlet side of said valve for supplying thereto a solvent liquid, and a delivery 90 nozzle for applying the solvent liquid to the margin of a stiffener connected to the handle upon the outlet side of said valve, said nozzle being parallel to and laterally offset from said handle to permit access of the nozzle to 95 the margin of the stiffener when the upper has been drawn over a last.

2. A device for softening the margin of a stiffener which has been incorporated in a partially lasted upper, having, in combination, a conduit for conveying a solvent liquid and having a constriction to retard the flow of liquid through said conduit and terminating in a delivery nozzle for applying the liquid to the stiffener, a valve in said conduit, 100 a reservoir for supplying a solvent liquid to said conduit and positioned above the normal working level of said nozzle to effect a flow of the liquid through said conduit, and means for adjusting the height of said reservoir relatively to the normal working level of said nozzle to vary the amount of liquid 105 allowed to pass by said constriction.

3. A device for softening the margin of a stiffener which has been incorporated in a 110 partially lasted upper, having, in combination, a conduit for conveying a solvent liquid and having an inlet and an outlet end, and a valve in said conduit having a valve chamber and a valve seat and having a valve 115 plunger adapted to cooperate with said valve seat to close said valve, said valve plunger extending through an opening in the wall of said chamber, whereby the closing movement of said valve plunger will displace liq- 120 125 130

uid within said valve chamber and force the displaced liquid toward the outlet end of said conduit, said conduit having a constriction on the outlet side of said valve for retarding the flow of liquid through said conduit.

4. A device for softening the margin of a stiffener which has been incorporated in a partially lasted upper, comprising a conduit adapted at one end to receive a supply of solvent liquid and at its opposite end to apply the liquid to the margin of the stiffener, and a plunger in said conduit adapted to displace by its movement a definite quantity of the liquid, said conduit being constructed and arranged to oppose the return of the displaced liquid toward the receiving end of said conduit, whereby the movement of said plunger will cause the delivery of a measured amount of the solvent liquid to the margin of the stiffener.

5. A device for delivering a solvent liquid to the margin of a stiffener which has been incorporated in a partially lasted upper, comprising a conduit having a supply end and a delivery end and constructed and arranged to effect a normal head of the solvent liquid at said delivery end, means for substantially preventing the flow of the liquid through said delivery end under the influence of said normal head alone, and means for momentarily augmenting said normal head to overcome said preventing means, thereby expelling a portion of the liquid within said conduit from said delivery end.

35 6. A device for delivering a solvent liquid to the margin of a stiffener which has been incorporated in a partially lasted upper, comprising a conduit having a supply end and a delivery end and constructed and arranged to effect a normal head of the solvent liquid at said delivery end, means for substantially preventing the flow of the liquid through said delivery end under the influence of said normal head alone, means for momentarily augmenting said normal head to overcome said preventing means, thereby expelling a portion of the liquid within said conduit from said delivery end, and means for varying said normal head, thereby to 50 vary the amount of the liquid expelled.

7. A nozzle for applying a solvent liquid to the margin of a stiffener which has been incorporated in a partially lasted upper, having a thin grooved end for distributing the liquid along the line of the upper to be treated and having a constricted passage opening into the groove of said end.

8. A nozzle for applying a solvent liquid to the margin of a stiffener which has been incorporated in a partially lasted upper, comprising a tube having a thin end and also having a longitudinal constricted passage and a groove transverse to said passage, said groove being disposed in the edge of said thin end, and said constricted passage open-

ing into said groove to supply liquid thereto.

9. A nozzle for applying a solvent liquid to the margin of a stiffener which has been incorporated in a partially lasted upper comprising a tube terminating in a thin fan-shaped end having a grooved edge to accommodate the general curvature of the stiffener and to distribute the solvent liquid along the line to be treated, said tube having a constricted passage opening into said groove to retard the flow of the liquid to said groove.

10. A device for softening the margin of a stiffener which has been incorporated in a partially lasted upper, comprising a nozzle, and operator-controlled means for delivering a solvent liquid intermittently in measured quantities to said nozzle, said nozzle being constructed and arranged to apply the solvent liquid continuously to the margin of the stiffener.

11. A device for softening the margin of a stiffener which has been incorporated in a partially lasted upper, comprising a nozzle having a grooved end for retaining liquid which may be received discontinuously by the nozzle and for continuously delivering such liquid for application to the margin of the stiffener, and means operable upon successive manipulations to supply at each manipulation a definite amount of the solvent liquid to said nozzle.
